UNITED STATES PATENT OFFICE.

BASIL G. AUSTIN, OF HARTFORD, CONNECTICUT, ASSIGNOR TO AUSTIN ORGAN COMPANY, OF HARTFORD, CONNECTICUT, A CORPORATION OF MAINE.

PIPE-ORGAN REED-PIPE.

1,323,436.

Specification of Letters Patent.

Patented Dec. 2, 1919.

Application filed August 14, 1918. Serial No. 249,775.

To all whom it may concern:

Be it known that I, BASIL G. AUSTIN, a citizen of the United States, residing at Hartford, in the county of Hartford and State of Connecticut, have invented certain new and useful Improvements in Pipe-Organ Reed-Pipes, of which the following is a specification.

This invention relates to a pipe-organ reed-pipe. I have several motives in view, one of the primary ones being the provision of means whereby the resonance of the pipe is increased or at least the sound more efficiently delivered. Another object is the provision of simple and effective means by which the pipe can be tuned and the adjustment necessary to secure the effect maintained in a proper manner.

In the drawings accompanying and forming part of the present specification I have shown in detail a form of embodiment of the invention which will be set forth fully in the following description, to enable those skilled in the art to practise the invention. I do not restrict myself to this particular disclosure; I may depart therefrom in several respects within the scope of the invention defined by the claims following said description.

Referring to said drawings:

Figure 1 is an elevation of an organ reed-pipe and its adjuncts involving the invention.

Fig. 2 is a sectional elevation of the intermediate portion of the structure shown in Fig. 1, on a larger scale.

Fig. 3 is a cross section on the line 3-3 of Fig. 2, looking in the direction of the arrows.

Like characters refer to like parts throughout the several views.

The organization involves in its make-up a boot as 2. In the enlarged end of this boot is removably fitted a block as 3 from which depends within the boot, the eschallot 4. Connected with the eschallot is a reed tongue as 5. There is also a tuning wire as 6. These parts in fact may be like those ordinarily in use. The boot constitutes a carrier for a bell or resonator such as that denoted in a general way by 7 and which although it may be of any suitable material, is customarily but not essentially made from sheet metal. The bell or resonator 7 comprises a body as 8 provided at what is known

as its lower end with a tubular tip 9, desirably made for a reason that will herein-after appear, in the form of a cylinder or practically circular in cross section, although this may not always be necessary. 60 From the top of the block extends the tube 10 up to the necessary height, and this tube 10 has a sliding connection with the tubular tip 9. As shown this tubular tip 9 surrounds and slides on the tube 10, the engaging surfaces of the two being smooth, that is not threaded. Although this is the preferable way of connecting these two elements, the union may be otherwise made. By reason of the fact that the engaging 70 surfaces of the tip 9 and tube 10 are plain, the relation of the resonator, except as to its longitudinal adjustments, need never be varied with respect to the auditors during such adjustments.

It will be understood that by moving the bell or resonator 7 longitudinally, its tubular tip 9 will be caused to telescope more or less the tube 10, this being done for tuning. There is means provided for maintaining the adjustment, this means obviously within certain limits varying. As shown it consists of a stop in the form of a clamp 11 slidable on the tube 10 and held in its adjusted relation by the screw 12. It will be 85 assumed that it is desired to tune. In this event the following procedure may be adopted: The screw 12 will be loosened, so that the clamp 11 will be freed from the tube 10, after which the tip 9 will be elevated on the tube 10 and the clamp set in the desired position, following which the resonator 7 will be adjusted so as to bring the end of the tube in solid and substantial engagement with the stop or clamp 11, the 90 screw 12 of which is then tightened to maintain the adjustment.

In the present case the bell or resonator is imperforate or non-slotted throughout its entire extent, differing in this respect as 100 I understand, from resonators of the ordinary character. The body 8 of the resonator is as I have already noted, of taper or frusto-conical form. This body 8 is furnished with a frusto-conical head 13 united 105 directly with the body 8 for instance by a joint 14 maintained by solder or other convenient means. The head 13 has its axis at an obtuse angle to the axis of the body 8 and its pitch or angle is greater than that 110

of the body. This head faces laterally of the body so as to throw out the sound or divert the same laterally instead of upwardly.

- 5 I desire again to call attention to one important fact and that is that the taper of the head 13 is different from that of the taper of the body 8 of the resonator. As shown the pitch or angle of the head is 10 greater than that of the body. I wish also to refer to the point that as shown the pitches of both the body and the head are respectively uniform.

What I claim is:

- 15 1. In a pipe-organ reed-pipe, a boot having a block fitted therein, the block being furnished with a tube, a bell provided with a tubular tip in sliding engagement with the tube for thus effecting the adjustment 20 of the bell, the engaging surfaces of the tube and the tip being smooth to permit the adjustment of the tip without turning, and means for positively maintaining the bell in an adjusted position on the tube.
- 26 2. In a pipe-organ reed-pipe, a boot hav-

ing a block fitted therein, the block being furnished with a tube, and a bell provided with a tubular tip in sliding engagement with and around the tube for thus effecting the adjustment of the bell, the engaging 30 surfaces of the tube and the tip being smooth to permit the adjustment of the tip without turning, and a stop adjustable on the tube provided with means for holding it in an adjusted position to be engaged by 35 the tip.

3. A pipe-organ reed-pipe comprising a conical body provided with a conical head united to the body at the larger end thereof, the union between the head and the body 40 being upon a plane obtuse to the longitudinal axis of the body, the taper of the head being greater than that of the body.

In testimony whereof I affix my signature in the presence of two witnesses.

BASIL G. AUSTIN.
